Patented Mar. 18, 1958

182,331

ADJUSTABLE ARMCHAIR

Roy A. Cramer, Kansas City, Mo., assignor to Cramer Posture Chair Company, Inc., Kansas City, Mo., a corporation of Missouri

Application May 14, 1956, Serial No. 41,471

Term of patent 7 years

(Cl. D15—1)

Fig. 1.

Des. 182,331

PAGE 2

Fig. 2.

Fig. 3.

Fig. 1 is a side perspective view of an adjustable armchair showing my new design;

Fig. 2 is a rear perspective view thereof; and

Fig. 3 is a front elevational view of the armchair.

The characteristic features of my design reside in the portions shown by means of full lines in the drawing.

I claim:

The ornamental design for an adjustable armchair, as shown and described.
